UNITED STATES PATENT OFFICE.

THOMAS ORTON, OF CHICAGO, ILLINOIS.

DESIGN FOR PAPER-CLIP.

Specification forming part of Design No. 6,830, dated August 26, 1873; application filed June 21, 1873.

To all whom it may concern:

Be it known that I, THOS. ORTON, of Chicago, county of Cook and State of Illinois, have invented certain new and useful Improvements in Designs for Paper-Clips, of which the following is a specification:

The nature of my design is fully represented in the accompanying photographic illustration, to which reference is made.

1 represents the frame, having the "pear-shaped" back 2 cut away, preferably at 3, so as to give it a light and graceful appearance, and carrying the lug 4.

The base consists of two semicircles, 6 6, extending outward at right angles to the back.

The awl 5, with milled head, passes through lug 4, extending to base 6.

The distinctive character of my design is the configuration of the back and base.

Having thus described my invention, what I claim as new, and desire to secure by Letters Patent, is—

The design for a paper-clip, when the different parts are arranged as specified.

In testimony that I claim the foregoing as my invention I hereunto affix my signature.

THOS. ORTON.

Witnesses:

GEO. C. FELTON,
JAS. S. DICKINSON.
